UNITED STATES PATENT OFFICE.

MARIO CAMAGNI, OF PATERSON, NEW JERSEY.

SHUTTLE.

1,194,816.

Specification of Letters Patent. Patented Aug. 15, 1916.

Application filed April 8, 1915. Serial No. 19,872.

To all whom it may concern:

Be it known that I, MARIO CAMAGNI, a citizen of the United States, residing at Paterson, in the county of Passaic and State 5 of New Jersey, have invented certain new and useful Improvements in Shuttles, of which the following is a specification.

Means heretofore proposed for securing the filling package on the spindle of a shuttle have been of such character that a cop-tube, forming the core of the package, would be usable but a very few times, due to its bore being so abraded or worn by the securing means that the latter's grip thereon 10 would cease to remain effectual to prevent slippage of the filling package more or less off the spindle in the violent back and forth movements of the shuttle.

The object of this invention is to provide 20 a spindle device for shuttles wherein this objection will be overcome. My invention makes it possible not only to use a cop-tube until it becomes useless from other causes than that attributable to any wear which 25 the improvement may engender, but to use cop-tubes varying widely in size on the same spindle.

In the accompanying drawing, Figure 1 is a view of a shuttle provided with my improved spindle, the shuttle and the cop-tube on the spindle appearing in section and the spindle being in its elevated position; Fig. 2 is a plan view, the spindle being depressed; and, Figs. 3 and 4 are a longitudinal sectional view of the spindle and a transverse sectional view on the line $x-x$ in Fig. 3.

In the shuttle a and fulcrumed on the pin b is the spindle c . 40 d is the cop-tube, in the present case formed of paper and tapering, according to custom.

The spindle is threaded, as at e , throughout approximately its whole length, and 45 preferably in its upper side it has a longitudinal groove f .

Screwed onto the spindle is the cop-grip member g , which is in the form of a sleeve of approximately the same diameter throughout 50 and internally threaded to engage the threading of the spindle. This cop-grip member is in the illustrated adaptation provided externally with serrations h and these are preferably in the form of threading. 55 At one end the cop-grip member has a notch i .

In the groove f is arranged a key j which is a piece of spring wire bowed or arched slightly, its arch upstanding in the groove, and having one end k projecting out of the 60 groove, being bent off more or less at right angles, as best shown in Fig. 3, and its other end l rebent upon itself. The key extends through the bore of the sleeve g and is retained therein by the best portion k and l 65 thereof. Upon sliding the key in the groove f toward the free end of the spindle, its end k may be engaged in the notch i of the sleeve g to prevent the latter turning, the key being held against displacement toward the butt of the spindle when thus engaged with the sleeve by frictional contact of its bowed portion with the bore of the sleeve.

It being remarked that the bores of cop-tubes are tapered, it will be apparent, in view of the foregoing, that cop-tubes varying widely in diameter may be effectually secured on the improved spindle, having first adjusted the cop-grip or sleeve longitudinally of the spindle so that when the tube is fully "home" on the spindle the cop-grip or sleeve will come at a point where it will grip the bore of the cop-tube. The adjustment of the sleeve or cop-grip is effected by forcing the key longitudinally toward the butt of the spindle until it clears the notch in the sleeve, then turning the sleeve one way or the other until it has been advanced to the desired position on the spindle, and finally employing the key to relock the sleeve against rotation.

By forming the serrations on the sleeve as screw-threading, when the tube is placed on the spindle and turned with some pressure toward the butt of the spindle the threading of the sleeve forms corresponding threading in the bore of the cop-tube, which thus becomes effectually held to the spindle from longitudinal displacement.

If the interior of a cop-tube becomes worn where engaged by the cop-grip, it is only necessary to adjust the latter farther toward the free end of the spindle, so that a fresh part of the bore of the cop-tube may be engaged thereby.

Having thus fully described my invention, what I claim as new and desire to secure by Letters Patent is:—

1. In combination, a spindle structure for 110 shuttles including a spindle proper and a cop-grip shorter than the spindle proper

- and adjustable longitudinally on and between the ends of the latter, the spindle structure having approximately the same general diameter in any transverse section thereof between the ends of the cop-grip, whereby a cop or cop tube having a conical bore may be slipped over and entirely house the cop-grip.
2. In combination, a spindle structure for 10 shuttles including a spindle proper and a cop-grip sleeve shorter than the spindle proper and adjustable longitudinally on and between the ends of the latter, the spindle structure having approximately the same general diameter in any transverse section thereof between the ends of the sleeve, whereby a cop or cop tube having a conical bore may be slipped over and entirely house the sleeve.
- 20 3. In combination, a threaded-shuttle spindle member, a cop-grip member screwed
- thereon, and adjustable by rotation thereon longitudinally thereof, and a key disengagably locking said members together against rotation of the cop-grip member on the 25 spindle member.
4. In combination, a spindle member, a sleeve member screwed thereon and adjustable by rotation thereon longitudinally thereof, and a spring extending between the 30 sleeve and spindle members and against each of them.
5. A shuttle spindle device including a spindle, a cop grip member rotative on substantially the longitudinal axis of the spindle and having a screw connection therewith, and means to secure the grip member against rotation in various positions to which it is advanced by screwing relatively to 35 said spindle.

In testimony whereof I affix my signature.

MARIO CAMAGNI.
